FLUID SYSTEMS

Borje Rosaen, Ann Arbor, Mich., assignor to The Rosaen Filter Company, Hazel Park, Mich., a corporation of Michigan

Filed June 21, 1963, Ser. No. 289,622
7 Claims. (Cl. 103—203)

The present invention relates to fluid systems and more particularly to such a system having a primary pump and means operable to maintain the suction line level of the primary pump during periods when the primary pump is not in operation.

Either due to the construction of the pump itself or the design of the fluid system in which the pump is being used, primary pumps quickly lose their prime in the suction line upon being deactivated. This requires a lengthy running time upon activation of the pump before the fluid will have been lifted in the suction line sufficiently to produce the required prime.

The present invention provides a low capacity auxiliary pump connected to the suction line of a fluid system and operable to maintain fluid in the suction line during those periods when the primary pump is not being used. In this way, when the primary pump is again activated, it will immediately begin to deliver fluid through the fluid circuit.

It is an object then of the present invention to reduce the starting up time for fluid systems by providing means for maintaining the fluid level in the suction line of such systems during those periods in which the pump is not in use.

It is another object of the present invention to increase the efficiency of fluid systems by providing means operable to remove accumulations of air in the filter housing of such systems during those periods in which the pump is being operated and also operable to maintain the fluid level in the suction line of such systems during those periods when the pump is not being used.

Still further objects and advantages will readily occur to one skilled in the art to which the invention pertains upon reference to the following drawings in which like reference characters refer to like parts throughout the several views and in which

FIG. 1 is a schematic drawing illustrating one preferred embodiment of the present invention and

FIG. 2 is a schematic drawing similar to FIG. 1 but illustrating another preferred embodiment of the present invention.

Description

Now referring to the drawings for a more detailed description of the present invention, a preferred filter system is illustrated schematically as comprising a fluid reservoir 10 partially filled with a suitable fluid 11. The reservoir 10 is provided with a top plate 12, a floor portion 13 and side walls 14. A primary pump 15 is preferably carried on the plate 12. The inlet side of the primary pump 15 is connected by a suction conduit 16 to the reservoir 10. The suction conduit 16 is provided with an inlet end 18 disposed within the reservoir 10 beneath the minimum level of the fluid 11. The outlet side of the primary pump 15 is connected by conduit 20 to a fluid user 21. A motoring means 22 is operably connected to the primary pump 15.

The suction conduit 16 is preferably provided with a substantially horizontally extending portion 24 and a branch conduit 26 is connected with the portion 24 as shown. The branch conduit 26 is connected with the inlet side of an auxiliary pump 28. The outlet side of the auxiliary pump 28 is connected by a return conduit 30 to the reservoir 10. The return conduit 30 is pref-

2

erably provided with an outlet 32 disposed within the reservoir 10 above the maximum level of the fluid 11. A slanted plate 34 is preferably secured to the sidewall 14 of the reservoir 10 in a position to intercept fluid emitted from the outlet 32. A motoring means 36 is operably drivingly connected to the auxiliary pump 28.

The auxiliary pump 28 needs only to have a capacity slightly larger than the potential air leakage of the primary pump 15. The auxiliary pump 28 may be left running at all times. Then when the primary pump 15 is deactivated, the auxiliary pump 28 will maintain fluid in the suction line 16 to the suction line level of the primary pump 15. In this way, the primary pump 15 will be ready to immediately deliver fluid to the system upon activation thereof.

Another preferred embodiment of the present invention is illustrated schematically in FIG. 2. A preferred fluid system is illustrated as comprising a reservoir 110 partially filled with a suitable fluid 111 and having a top plate 112, a floor portion 113 and sidewalls 114.

The inlet side of a primary pump 115 is preferably connected with the reservoir 110 by a suction conduit 116. The suction conduit 116 is provided with an inlet end 118 disposed within the reservoir 110 below the minimum level of the fluid 111. The outlet side of the primary pump 115 is connected by conduit 120 to a fluid user 121. A motoring means 122 is operably drivingly connected to the primary pump 115.

A filter device 124 is connected in the suction conduit 116 intermediate the inlet side of the primary pump 115 and the reservoir 110. The filter device 124 preferably comprises a housing 136 having a filter chamber 137, an inlet 138 and an outlet 140 communicating with the chamber 137. A substantially cylindrical filter element 142 is carried in the chamber 137 intermediate the inlet 138 and the outlet 140.

A conduit 144 communicates with the upper portion of the chamber 137 and is connected with the intake side of an auxiliary pump 128. The discharge side of the auxiliary pump 128 is connected with the reservoir 110 by a return conduit 130. The return conduit 130 is provided with an outlet end 132 disposed within the reservoir 110 above the maximum level of the fluid 111. A motoring means 136 is operably drivingly connected with the auxiliary pump 128.

The operation of the system illustrated in FIG. 2 is substantially similar to that described above with reference to FIG. 1 except that by connecting the auxiliary pump 128 to the upper portion of the filter device 124 as shown the auxiliary pump 128 will remove the air which ordinarily accumulates in the filter housing 136.

Although I have described several preferred embodiments of the present invention, it is apparent that many other changes and modifications can be made without departing from the spirit of the invention.

I claim:

1. A fluid system comprising
  - (a) a fluid reservoir and a fluid user,
  - (b) a selectively operable primary pump and conduit means connecting the intake side of said primary pump with said fluid reservoir and the discharge side of said primary pump with said fluid user,
  - (c) an auxiliary pumping means of a smaller capacity than said primary pump and having an intake side connected to said conduit means intermediate said primary pump and said fluid reservoir and a discharge side connected with said fluid reservoir whereby said auxiliary pumping means is operable to maintain fluid in said conduit means intermediate said primary pump and said fluid reservoir during periods of deactivation of said primary pumping means, and

(d) a filter device carried in said conduit means intermediate said primary pump and said fluid reservoir and said auxiliary pump being connected with said filter device.

2. The fluid system as defined in claim 1 and wherein said filter device is carried in said conduit means intermediate said primary pump and said fluid reservoir,

(a) said filter device comprising a housing having a filter chamber and a filter element carried in said chamber, and

(b) said auxiliary pump having its intake side connected with the upper portion of said filter chamber.

3. In a fluid system having a fluid user and a fluid reservoir,

(a) a selectively operable primary pumping means including a suction conduit adapted for insertion into said fluid reservoir and a discharge conduit adapted for connection with said fluid user, and

(b) an auxiliary pumping means of a smaller capacity than said primary pumping means having an intake side connected with said suction conduit and a discharge side adapted for connection with said fluid reservoir whereby said auxiliary pumping means is operable to maintain fluid in said suction conduit during periods of deactivation of said primary pumping means, and

(c) a filter device carried in said suction conduit and said auxiliary pump being connected with said filter device.

4. The fluid system as defined in claim 3, and in which

(a) said filter device comprises a housing, a filter chamber and a filter element carried in said chamber, and

(b) said auxiliary pump having its intake side connected with the upper portion of said filter chamber.

5. A fluid system comprising

(a) a fluid reservoir and a fluid user,

(b) a selectively operable primary pumping means and conduit means connecting the intake side of said primary pumping means with said reservoir and the discharge side of said primary pumping means with said user,

(c) a suction means of a smaller capacity than said primary pumping means and having an intake connected to said conduit means intermediate said primary pump and said fluid reservoir and a discharge

side connected with said reservoir whereby said suction means is operable to maintain fluid in said conduit means intermediate said primary pump and said fluid reservoir during periods of deactivation of said primary pumping means, and

(d) a filter device carried in said conduit means intermediate said primary pumping means and said fluid reservoir, and said suction means being connected with said filter device.

6. The fluid system as defined in claim 5, and in which

(a) said filter device comprises a housing having a filter chamber and a filter element carried in said chamber,

(b) said suction means having its intake side connected with the upper portion of said filter chamber.

7. A fluid system comprising

(a) a fluid reservoir and a fluid user,

(b) a selectively operable primary pump disposed

above the fluid level in said reservoir,

(c) conduit means connecting the intake side of said primary pump with said fluid reservoir and the discharge side of said pump with said fluid user,

(d) a filter device carried in said conduit means intermediate said primary pump and said fluid reservoir and disposed at substantially the same elevation as the intake of said pump,

(e) and an auxiliary pumping means of a smaller capacity than said primary pump and having an intake side connected to the interior of said filter device and a discharge side connected with said fluid reservoir, said auxiliary pumping means being continuously operable to maintain fluid in said filter and thereby remove air therein so as to provide immediate priming of said primary pump.
